UNITED STATES PATENT OFFICE.

THEODORE N. ELY AND JOHN W. CLOUD, OF ALTOONA, PENNSYLVANIA,
AND EDWARD B. WALL, OF COLUMBUS, OHIO.

REFRIGERATOR-CAR.

SPECIFICATION forming part of Letters Patent No. 290,324, dated December 18, 1883.

Application filed July 24, 1883. (No model.)

To all whom it may concern:

Be it known that we, THEODORE N. ELY and JOHN W. CLOUD, both of Altoona, Pennsylvania, and EDWARD B. WALL, of Columbus, Ohio, have invented a new and useful Improvement in Refrigerators, of which the following is a full, true, and accurate account, reference being had to the accompanying drawings, which form a part of this specification.

Our invention has especial reference to that class of refrigerators in which ice is used to produce the requisite low temperature, and has for its object the perfection of the circulation of air through the refrigerator-chamber, the economical use of the ice employed to cool the air, and the drying and cleansing of the air as it circulates.

Our invention accordingly consists in the devices for distributing the cooled air in such a way as to insure its circulation through the chamber, in devices for condensing the water held in suspension in the cooled air, and in the mechanical constructions and arrangements hereinafter described.

Reference being now had to the drawings, in which similar letters designate similar parts, Figures 1, 2, 3, and 4 are sectional views of our invention as applied to stationary refrigerators; and Figs. 5 and 6 respectively longitudinal and transverse sections of a refrigerator-car embodying our invention.

A is the chamber to be cooled.

B is the ice-box, which is situated at the top 35 of the refrigerator.

C is a flue opening at its top into the ice-box B, and extending down nearly to the bottom of the chamber.

D D are metallic plates or diaphragms, 40 which we place inside of the flue C, and preferably parallel with it, so that as little resistance shall be offered to the descending air as is possible.

E is a drip-dish, provided with a trap.

F F are openings at the top of the ice-box 45 for the admission of air.

b b are gratings or bars placed over the entrance to the flue C, to prevent ice from falling into it from the ice-box B. The walls of 50 the ice-box and flue are made up of an outer

skin, g, of wood or other similar poor conductor of heat, and of an inner metallic skin, h. The walls of the refrigerator are preferably of wood or similar material. We prefer to make the bottom of the ice-box B so that it 55 will slope toward the flue C, and to corrugate its inner metallic skin, as shown at h' in Figs. 3 and 6. By causing the air to enter the ice-box at the highest possible point and not allowing it to escape from the flue, which forms 60 a prolongation of the ice-box, until it is at or nearly at the bottom of the chamber to be cooled, we obtain a more perfect and powerful circulation through the chamber from bottom to top than can be obtained by any other 65 means. The interior metal lining, h, of the ice-box and flues and the metal diaphragms D promote the condensation of the moisture in the air passing through the flues, and constitute ample and suitable surfaces on which the 70 water can be deposited. The water will run down from the flue and diaphragms into the drip pan or trough E, and by means of the trap with which it is provided will escape outside of the refrigerator without allowing 75 the admission of any air. It is evident that the form and number of the diaphragms D may be varied at will, the only limitations on their manner of construction being that they shall present a sufficiently large surface upon 80 which the water may condense, and be so arranged in the flue C as not to materially interfere with or check the descending current of air. The corrugations h' of the bottom of the ice-box conduct the water from the melting 85 ice direct to the flue C, and deliver it in a thin even stream. The bottom and outside, g, of the ice-box and flue being of wood or similar non-conducting material, there will be no tendency for the water to deposit upon them, and 90 the current through the chamber will be a drying as well as a cooling one.

Where the ice has a tendency to pack in the ice-box it will be well to place a grating or slatted box in the ice-chamber, so that the 95 air may circulate under or alongside of the ice without passing through it. Such a construction is shown in Figs. 1 and 3. The same difficulty is also overcome by us by placing bars or gratings b b over the mouth of the flue C in 100

such a way that they shall project upward to or even above the level of the ice in the box. Their upward slant from the edge of the flue serves at the same time to keep the ice from falling into the flue, and enables the air after passing over the ice to find its way down into the flue without passing through much or any of the ice. Provisions of this kind to insure an uninterrupted current of air are of the utmost importance, as if the mouth of the flue C becomes choked with ice the cooling of the chamber would be very imperfect, and the moisture would condense in the chamber and on its contents.

15 Where it is practicable we prefer to construct the flue C in the center of the chamber to be cooled, and provide entrances for the air all around the top of the ice-box, as this construction will, we think, secure the most perfect circulation of the cooled air. Fig. 3 is intended to illustrate such an arrangement, and shows how in a refrigerator with two side doors the flue would be placed. As will be seen, its central position would offer no obstacle to getting at any part of the interior of the chamber.

Having now described our invention, what we claim as new, and desire to secure by Letters Patent, is—

30 1. In a refrigerator substantially as described, the combination of the ice-box B, situated at the top of the chamber A, and having openings F at its top, the metal-lined flue C, extending from the ice-box B to the bottom of the chamber A, and the drip-cup and trap E, situated beneath the end of the flue C.

2. In a refrigerator substantially as described, the combination of the ice-box B, situated at the top of the chamber A, and having openings F at its top, the metal-lined flue C, extending from the ice-box B to the bottom of

the chamber A, the metal diaphragms D, situated in the interior of the flue C, and the drip-cup and trap E, situated beneath the end of the flue C.

3. In a refrigerator substantially as described, the combination of the ice-box B, situated at the top of the chamber A, and having openings F at its top, the flue C, extending from the ice-box B to the bottom of the chamber A, the metal diaphragms D, situated in the interior of the flue C, and the drip-cup and trap E, situated beneath the end of the flue C.

4. In a refrigerator substantially as shown and described, the chamber A, having non-conducting sides, in combination with the ice-box B, having its outer skin, g, of non-conducting material, the flue C, having its outer skin of non-conducting material and its inner skin, h, of metal, and drip-cup and trap E.

5. In a refrigerator substantially as shown and described, the chamber A, having non-conducting sides, in combination with the ice-box B, having its outer skin, g, of non-conducting material, and its inner skin, h', of corrugated metal, the flue C, having its outer skin of non-conducting material and its inner skin, h, of metal, and drip-cup and trap E.

In testimony whereof we have hereunto set our hands.

THEO. N. ELY.
JOHN W. CLOUD.
EDWD. B. WALL.
